US00D862421S

(12) **United States Design Patent** (10) **Patent No.:** **US D862,421 S**
Arimoto (45) **Date of Patent:** **** Oct. 8, 2019**

(54) **REMOTE CONTROL FOR EARPHONE**

(71) Applicant: **JVC KENWOOD Corporation**,
Yokohama-shi, Kanagawa (JP)

(72) Inventor: **Takuya Arimoto**, Yokohama (JP)

(73) Assignee: **JVC KENWOOD Corporation**,
Yokohama-Shi (JP)

(**) Term: **15 Years**

(21) Appl. No.: **29/615,029**

(22) Filed: **Aug. 25, 2017**

(30) **Foreign Application Priority Data**

Apr. 14, 2017 (JP) 2017-008042

(51) **LOC (12) Cl.** **14-03**

(52) **U.S. Cl.**

USPC **D14/218**

(58) **Field of Classification Search**

USPC D14/218; D13/168

CPC G09G 5/00; G06F 3/033

See application file for complete search history.

(57) **CLAIM**

The ornamental design for a remote control for earphone, as shown and described.

DESCRIPTION

FIG. 1 is a front and right-side perspective view of a remote control for earphone showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof;

FIG. 7 is a left-side elevational view thereof; and,

FIG. 8 is a reference perspective view thereof, showing a state for use with earphone and cables.

The broken lines depict portions of the remote control for earphone that form no part of the claimed design. In FIG. 8, the broken lines showing of earphone and cables illustrate environment and form no part of the claimed design.

1 Claim, 5 Drawing Sheets
